UNITED STATES PATENT OFFICE

164,167

VEHICULAR TRAILER

Alice J. Grossniklaus, Wilmot, Ohio

Application September 15, 1950, Serial No. 12,201

Term of patent 14 years

(Cl. D14—3)

To all whom it may concern:

Be it known that I, Alice J. Grossniklaus, a citizen of the United States, residing at Wilmot, in the county of Holmes, and State of Ohio, have invented a new, original, and ornamental Design for a Vehicular Trailer, of which the following is a specification, reference being had to the accompanying drawing, forming part hereof.

Fig. 2 is an elevational view of one end thereof; and

Fig. 3 is an elevational view of the opposite end thereof.

The opposite side of the trailer is substantially similar to the side shown in Fig. 1. The drawing is lined to indicate color. The dominant features of my design reside in the portions shown in full lines.

I claim:

The ornamental design for a vehicular trailer, substantially as shown and described.

ALICE J. GROSSNIKLAUS.
